RADIO RECEIVER

Harry Whalley, Darwen, and Charles Walter Miller, Sale, England, assignors to Metropolitan-Vickers Electrical Company Limited, London, England, a company of Great Britain

Application December 16, 1943, Serial No. 514,478
In England August 8, 1941

1 Claim. (Cl. 250—20)

1

This invention relates specifically to so-called panoramic radio receivers the nature of which was described in "Electronics," June, 1940 and wherein, in brief, a waveband or it may be any selected one of a plurality of wavebands, is scanned from end to end by the automatic variation of a tuning parameter at a rate comparable with the frequency of the persistence of vision, the output or outputs due to any received radio transmissions which may be taking place within the waveband being indicated as resonance or peak components perpendicular to a time base waveband component on the screen of a cathode ray tube, the time base component being provided synchronously with the scanning such as by means of a saw-tooth type of oscillation generator. Provision can be made whereby any selected one of the thus indicated transmissions can be tuned into manually and its modulation listened to or recorded or otherwise indicated, that is to say, the scanning of the waveband can be effected solely by hand such as through the turning of a knob about an associated dial indicating the wavelength. In such a panoramic receiver it has been convenient for the purpose of the rapid scanning of the waveband to "wobble" the value of certain tuning components of the oscillator section of a frequency changer valve in a superheterodyne circuit, which superheterodyne circuit preferably has three stages of frequency changing with corresponding intermediate frequency circuits, and preferably the scanning is effected by a reactor valve associated with the second of the oscillators through an amplifier as described in United States application Serial No. 503,277, filed September 21, 1943.

What has been called the "single-span" tuning principle in domestic and other radio receivers has been proposed but has not apparently come into commercial use.

The general advantages of the superheterodyne receiver over other types are also well known and its use in a panoramic receiver is highly desirable, and when panoramic receivers are required to scan a relatively large number of wavebands, for instance twenty or thirty, there may be great complexity and expense unless provision is made for reducing the number of preset tuning circuits which have to be changed when the waveband to be scanned is altered. In order that the received signals shall have sufficient amplitude at the first frequency changer to override valve noise in the mixer some signal frequency amplification is generally desirable. It is, however, also desirable that "image" frequency signals are removed as

2

far as possible from the wavebands covered by the receiver.

The invention is based on the above considerations which are given in greater detail in the following statement which includes further considerations.

In general a satisfactory panoramic receiver should have *a* high sensitivity to enable the maximum number of signals to be observed, *b* the selectivity should be high to give adequate discrimination between adjacent signals, consistent with the tuned circuits being able to respond at the rate of time base sweep and of scanning synchronously therewith, *c* it is desirable at the same time that second channel interference should be absent or substantially absent; *d* the process of scanning should involve the smallest number of tuning parameters as possible; and *e* tuning can be conveniently carried out by electronic rather than mechanical means.

Regarding *a* above, this involves high overall gain which is conveniently obtainable by the use of an amplifier of standard design operated at, for example, 1.6 mc. per second or 465 kc. per second. This will also satisfy requirement *b* above while the consequent use of a superheterodyne circuit simplifies the requirement *d* above but it introduces the difficulty of second channel interference *c* above. As an example, a particular receiver may be quoted which was required to cover a frequency range of from fifteen to thirty megacycles per second in thirty consecutive bands each of five hundred kilocycles per second width; such receiver therefore had to be capable of tuning automatically through five hundred kilocycles per second on each of the bands at a recurrence frequency of the order of twenty-five per second. To achieve this mechanically with normal input circuits would have involved the use of at least two

continuously variable tuning devices such as automatically rotating condensers, as well as complicated band switching means to cover the necessary number of bands. If the tuning were to be effected electronically such as by means of a reactor valve, the switching would not be simplified; therefore a preliminary frequency changing stage (it is preceded by a signal frequency amplifier) was proposed for converting all signals to a frequency band of five hundred kilocycles per second in width so that a single automatically variable oscillator and its associated frequency changer would suffice to produce the panoramic sweeps, irrespective of the band to which the receiver was adjusted.

According to the present invention a panoramic

receiver has at least two and preferably three frequency changer stages with aperiodic signal frequency amplification prior to the first stage, whilst the first oscillator frequency is high for giving a first intermediate frequency higher than any signal frequency so that the tuned circuit elements, preferably condensers only, which have to be selectively switched to the fixed element of the receiver for frequency band changing are reduced, namely to those of the oscillator circuit because the image frequency is so high that it can easily be filtered out, or is even inherently eliminated. The aperiodic signal frequency amplifier does not increase the selectivity and gives only a small gain, but it has been found in the combination above set forth to give satisfactory performance in practice and also, due to its inability to deal with such high frequencies, helps to filter out the image frequencies. The first intermediate frequency amplifier circuit preferably has a band-pass characteristic of adequate frequency width which may be, for example, five hundred kilocycles per second so that the frequency wobbling can be done at the second oscillator, thus enabling all bands selected to have an equal width.

In an example of panoramic receiver in accordance with the invention for a signal frequency range of fifteen to thirty megacycles in steps of five hundred kilocycles per second, the first oscillator frequency is from forty-eight to sixty-three megacycles per second and the mid-frequency to which the intermediate frequency amplifier is tuned is thirty-three megacycles per second, the image frequency being from eighty-one to ninety-six megacycles per second.

Thus the present invention employs the per se known single span principle in a panoramic receiver, particularly in cases where the frequencies are so chosen that aperiodic signal frequency circuits are permissible and yet second channel interference is avoided, whilst the choice of band to be observed is decided merely by the tuning of the first oscillator. The use of this arrangement in conjunction with a main intermediate frequency amplifier with its frequencies chosen appropriately, enables adequate selectivity, sensitivity and freedom from second channel interference to be obtained, in spite of the simple nature of the input circuits and the necessarily wide frequency band passed by the first intermediate frequency amplifier. It is to be understood that we do not herein claim per se automatically varying the tuning of the second oscillator instead of the first, in a panoramic receiver.

The accompanying drawing is a block diagram indicating a particular panoramic radio receiver in accordance with the present invention.

Starting from the left-hand end of the diagram the rectangle A. R. F. A. represents the desirable

radio frequency amplifier stage which is aperiodic, at least within the band to be scanned. M. 1 is the first mixer stage supplied from A. R. F. A. and from the first oscillator 0.1 having a frequency, in the particular example, of 33 megacycles per second plus the mid-frequency of the band of signals being scanned. It is assumed that the scanning is over a band of one-half megacycle. I. F. A. 1 is the first intermediate frequency amplifier, which may include a filter which responds uniformly over the band, in the example 33 mc. $\pm$ 250 kc./sec. and attenuates outside it. M. 2 is the second mixer stage supplied from I. F. A. 1 and from the second oscillator 0.2 the frequency of which, in the example, is wobbled between the limits of 34.35 and 34.85 mc./sec. I. F. A. 2 is the second intermediate frequency amplifier, sharply tuned to 1.6 mc./sec. M. 3 is the third mixer stage, supplied from I. F. A. 2 and from the third oscillator 0.3, the frequency of which is 2.065 mc./sec. The mixer M. 3 feeds to the third intermediate frequency amplifier I. F. A. 3 tuned to 465 kc./sec., this amplifier feeding to the detector D which is preferably associated with a limiter L in accordance with United States Application Serial No. 503,280, filed September 21, 1943. The rectangle B. F. O. represents the beat frequency oscillator which may be used for heterodyning a continuous wave signal in order to obtain an audible beat note if desired.

The output from the detector goes, on the one hand, to the audio frequency amplifier A. A. supplying the phones Ph. or loud speaker or other indicating device, and, on the other hand, to the video amplifier V. A., the output of which is taken to the cathode ray tube represented by the rectangle C. R. T. The time base of the latter is fed from the time base generator represented by the rectangle T. B. G., the output of which is also applied to the second oscillator 0.2 to wobble the normally fixed frequency of the latter in synchronism with the time base of the cathode ray tube over a band of 500 kilocycles.

We claim:

45 In a panoramic receiver, an input radio frequency amplifier stage aperiodic over the range of signals to be received, a first frequency changer stage variable to select a band of frequencies of substantially constant width to be scanned and arranged to convert the selected band to an intermediate frequency higher than that of the received signal, an intermediate frequency amplifier, a second frequency changer stage for scanning the band selected by the first frequency changer stage, means for varying the oscillator frequency of said second frequency changer stage to effect panoramic scanning, and a detector stage for the scanned signals.

60 HARRY WHALLEY.
